UNITED STATES PATENT OFFICE.

FRANK CARTLIDGE, OF CLAREMONT, NEW HAMPSHIRE, ASSIGNOR TO SULLIVAN MACHINERY COMPANY, A CORPORATION OF MASSACHUSETTS.

MINING-MACHINE TRUCK.

1,401,759.

Specification of Letters Patent. Patented Dec. 27, 1921.

Application filed October 10, 1917. Serial No. 195,754.

To all whom it may concern:

Be it known that I, FRANK CARTLIDGE, a citizen of the United States, residing at Claremont, in the county of Sullivan and 6 State of New Hampshire, have invented certain new and useful Improvements in Mining-Machine Trucks, of which the following is a full, clear, and exact specification.

My invention relates to mining machine 10 trucks.

It has for its object to provide an improved truck especially adapted to use in connection with loading or unloading mining machines, the same being provided with improved and simplified means whereby the loading or unloading of the mining machine is facilitated. A further object of my invention is to provide a truck having an improved and simplified loading and unloading 15 member adapted to coöperate automatically with the truck and mining machine during the movement of the latter toward or from the truck, and adapted to be readily adjusted toward or from its operative position 20 25 and carried during transport in a convenient position on the truck. These and other objects and advantages of my improved construction will, however, herein-after more fully appear.

30 In the accompanying drawings, I have shown for purposes of illustration one embodiment which my invention may assume in practice, illustrating the same as applied to a mining machine truck of standard form.

35 In these drawings,—

Figure 1 is a side elevation of a truck equipped with my improvement, a mining machine being shown in unloaded position with respect thereto and about to be drawn 40 thereon.

Fig. 2 is a side elevation of the truck shown in Fig. 1, the mining machine being illustrated as partially loaded.

Fig. 3 is a side elevation of the truck 45 shown in Fig. 1, the mining machine being shown loaded and the loading and unloading member in position for transport.

Fig. 4 is a plan view of the truck, the loading and unloading member being shown 50 in full lines in loading or unloading position and in dotted lines in transport position.

Fig. 5 is a longitudinal sectional view taken on line 5—5 of Fig. 4.

Fig. 6 is a detail transverse sectional view taken on line 6—6 of Fig. 4. 55

Fig. 7 is a transverse sectional view taken on line 7—7 of Fig. 4.

In this illustrative construction, it will be noted that I have shown a standard mule car or truck comprising the usual machine guiding member 1, preferably formed of upturned angle iron and mounted on truck wheels 2 and 3, which are in turn movable over the rails 4, and that this truck is illustrated as provided with a chain fork 5 adapted to receive the chain 6 of a self-propelled mining machine 7 and form an abutment whereby as the machine is fed along the chain the machine will be drawn onto the truck. 70

In my improvement, it will be noted that the guide members 1 of the truck extend a substantial distance in front of the front wheels 2 and are provided near their front ends and on their vertical flanges with suitable oppositely disposed brackets 8 having depending portions 9, and that in these portions 9 is journaled a transverse shaft 10 extending across beneath the members 1. Upon this shaft 10 there are rotatably and 75 releasably mounted, at points adjacent each of the depending portions 9, substantially U-shaped members 11 having arms 12 and 13 disposed on opposite sides of the shaft 10, and longitudinally disposed supporting and guiding members 14 projecting forwardly therefrom. As shown, these members 14 are

preferably formed of inverted channel irons fixed together or, if desired, to a smooth upper plate, in such a manner as to form a single rigid loading and unloading member 15 adapted to form a machine guiding extension of the truck frame. It will also be observed that the front ends of the vertical flanges of the members 14 are preferably 80 cut off, as shown at 16, in such a manner as to enable these portions to rest substantially flat upon the mine bottom when the member 15 is in the position shown in Fig. 1. It

will also be noted that I have provided each 85 of the members 11 with a rearwardly extending projection 17, preferably having a flat surface 18 on its end adapted to engage with the under side of the members 1

90 when the parts are in the position illustrated 95 in Fig. 1 and thus hold the member 15 sub- 100 105

stantially rigid, one end of the same resting upon the ground while the other end engages the bottom of the truck. Attention is also directed to the fact that I have provided a depending supporting means, shown herein in the form of a transverse strip 19, located at a point in rear of the brackets 8 and substantially midway between the same and the front wheels 2, which support is adapted to guide and underlie the member 15 when the arms 12 on the members 11 are lifted out of engagement with the shaft 10 and the member 15 is lifted and moved bodily backward under the truck frame, as shown in Fig. 3. It will also be noted that closely adjacent the front wheels 2 I have also provided stops or supports 20 adapted to limit the rearward movement of the member 15 and underlie the projections 17. Thus, obviously, due to the combined action of the shaft 10, the support 19, and the stops or supports 20, the member 15 will be securely maintained in its inoperative position during transport.

In considering the operation of a truck of my improved construction, let us first assume that it is desired to use the same in loading a machine, and that the parts occupy the position shown in Fig. 1. Obviously, due to the location of the member 15, the same will then provide an inclined surface over which the mining machine 7 may ride when its motor is started, in such a manner as to cause it to be fed along its chain 6, the rear end of which is attached to the chain fork 5. Due to the provision of the tapered front end 16 on the member 15, it will also be observed that the machine may very readily pass onto the member 15, and that, due to the provision of the low pivot for this member, the inclination leading to the truck will be relatively gradual. Attention is also directed to the fact that, due to the provision of the portions 17, 18 on the members 11, a substantially rigid construction is provided which acts during the first few inches or more of movement of the mining machine to prevent or resist upward buckling of the parts about the pivotal connection between the truck body and the extension 15, due to the inward thrust at the opposite ends of the structure as a whole, thereby enabling the front ends of the member 15 to be inserted under the mining machine before any flexure occurs in the joint between the member 15 and the truck. As the mining machine continues to travel up over the member 15, however, due to the weight of the machine the pivotal connection will obviously collapse, the rear end of the truck being raised and the parts assuming the position shown in Fig. 2. Obviously, the mining machine after having passed over the end of the member 15, will also be held elevated by that member and thus deflected over the front end of the truck members 1 so that it may readily ride up those members on the then tilted truck. During this movement, the front end of the machine will rest upon its bar in a well known manner until the center of gravity of the machine has passed over the center of gravity of the truck, whereupon the rear end of the latter will be lowered in such a manner as to bring the truck body and machine into the transport position illustrated in Fig. 3. When the machine has reached this position, the member 15 may readily be adjusted into its transport position, likewise shown in Fig. 3, by simply raising its inner ends in such a manner as to disengage the members 12 from the shaft 10, and then bodily sliding the entire loading and unloading member over the shaft 10 into the position shown in Fig. 3 with its rear end resting upon the supports 20, whereupon the entire truck is ready for movement about the mine. In unloading, after the member 15 by a reverse movement has again been moved to the position shown in Fig. 1, substantially the reverse of this operation takes place, although it will of course be understood that at that time the mining machine chain 6 is then connected to a point adjacent the face so that the machine is moved in the opposite direction. More specifically, it will be noted that as the machine moves forward over the truck the weight of the same will depress the front end of the truck in such a manner as again to make the member 15 assume the position shown in Fig. 2, and that as the machine passes farther off of the truck, the weight of the rear end of the truck will be sufficient to return that end of the truck to the track and raise the front end of the same and the member 15 into the loading position shown in Fig. 1, where the parts may remain until it is again desired to load the machine.

As a result of my improvement, it will be observed that it is possible to load and unload the machine with great facility and at the same time decrease the power required. In this connection, attention is also directed to the fact that not only does the loading and unloading member formed by the members 14, due to its temporarily rigid connection to the truck frame, assist materially in the initial stages of the loading operation, *i.e.* the process of getting the front tapered ends of the member under the machine, but that, due to its pivotal connection to the frame and the fact that this pivotal connection is lowered, the loading and unloading member also acts to decrease the angle at which the truck frame is disposed relative to the ground during the loading or unloading operation. It will also be observed that my improved structure is of exceedingly simple form, adapted to be manufactured at

very small expense and applied with great facility to mining machine trucks of any standard form without material change therein. These and other advantages of my improvement will, however, be clearly apparent to those skilled in the art.

While I have in this application specifically described one embodiment which my invention may assume in practice, it will be understood that this form of the same is shown for purposes of illustration, and that the invention may be modified and embodied in various other forms without departing from its spirit, it being my intention to include all such modifications within the scope of the appended claims.

What I claim as new and desire to secure by Letters Patent is:

1. In a mining machine truck, a truck frame, and a machine guiding extension pivotally connected thereto and forming a collapsible joint therewith.

2. In a mining machine truck, a truck frame, an inclined machine guiding member pivotally connected thereto, and operative connections between said members for resisting movement thereof about the pivot.

3. In a mining machine truck, a truck frame, a machine guiding extension pivoted thereto, and means resisting movement of said parts about the pivot prior to the tilting of said frame.

4. In a mining machine truck, a truck frame, a machine guiding extension pivoted thereto, and means for resisting upward movement of said parts about the pivot.

5. In a mining machine truck, a truck frame, and a machine guiding extension pivotally connected thereto and forming a downwardly collapsible joint therewith, said parts having provision for resisting upward collapse of said joint.

6. In a mining machine truck, a truck frame, an inclined machine guiding extension pivoted thereto, and means on the rearward end of said extension for limiting the upward movement thereof.

7. In a mining machine truck, a truck frame, an inclined machine guiding extension pivoted thereto, and means forming a projection on said extension extending beneath said frame and adapted to engage the same.

8. In a mining machine truck, a truck frame, an inclined machine guiding extension, and means for pivotally connecting the same at a point beneath the front end of said frame.

9. In a mining machine truck, a truck frame, a pivotally connected inclined machine guiding extension, and supporting means for said extension disposed beneath said frame and having one of its elements forming a pivot therefor.

65 10. In a mining machine truck, a truck

frame, an inclined machine guiding member, and means whereby as a load is drawn over said member the latter is depressed and said frame tilted.

11. In a mining machine truck, a truck frame, and an unloading member normally disposed beneath said frame and bodily movable longitudinally into operative relation in front of the same and at an angle relative thereto.

12. In a mining machine truck, a truck frame, a machine guiding extension disposed at an angle to the horizontal, and means whereby said member may be bodily reciprocated into transport position beneath said frame.

13. In a mining machine truck, a truck frame, a machine guiding extension pivotally connected thereto, and means whereby said member may be disengaged therefrom and reciprocated into inoperative position beneath said frame.

14. In a mining machine truck, a wheeled truck frame having its front end extending a substantial distance in front of its wheels, a machine guiding member pivotally connected at a point beneath said front end, and means for supporting said member in telescopic position beneath the front end of said frame.

15. In a mining machine truck, a wheeled truck frame, means forming pivot members disposed at the front end of said frame at a substantial distance in front of the truck wheels, and a machine guiding member having an elevated rear end pivoted on said pivot members and a front ground-engaging end, said member having means on its rear end engageable with a portion of the truck when said machine guiding member is disposed at an angle with respect to the ground.

16. In a mining machine truck, a wheeled truck frame, means forming pivot members disposed beneath the front end of said frame at a substantial distance in front of the truck wheels, a machine guiding member having a front ground-engaging end and having means on its rear end engageable with a portion of the truck when said machine guiding member is disposed at an angle with respect to the ground, and co-operating means for supporting said member beneath the front end of said truck when the front end of the said member is lifted and the same is shifted bodily rearward.

17. In an apparatus of the character described, the combination with a truck structure comprising a frame member and an inclined guiding member pivoted thereto adjacent one end thereof, of loading means adapted to cause thrust to be exerted upon said members respectively in opposite directions toward the pivot, said structure having provision for resisting relative movement of said members about said pivot to

decrease the dihedral angle formed between the lower sides of said frame member and said guiding member.

18. In an apparatus of the character described, the combination with a truck comprising a frame and an inclined machine guiding extension pivoted thereto adjacent its forward end, of a mining machine having feeding means including a feeding member adapted to be secured to said truck frame adjacent its rear end, and means for preventing upward movement of said frame and extension about their pivotal connection when said machine is drawn into engagement with the forward end of said extension by said guiding means.

19. A mining machine truck comprising a pair of machine guiding elements adapted to be angularly disposed relative to each other when in position for a mining machine to be loaded on said truck, one end of one of said members being adapted to be engaged beneath the front of the mining machine and the remote end of the other having means for the connection of a member under tension for hauling the mining

machine onto said truck, and means for limiting the angle formed by the planes of the upper sides of said elements.

20. A mining machine truck comprising a plurality of pairs of wheels, means for loading a mining machine into position for transport on said wheels and for supporting it thereon comprising a plurality of pivotally connected machine guiding members one of which is adapted to be initially engaged by a mining machine as it moves onto the truck and to the other of which means for hauling the machine onto the truck may be connected at the opposite end thereof, one of said pairs of wheels being nearer the pivotal connection between said members than the other, and means operative to prevent the elevation off the ground of the pair of wheels nearer said pivot during loading of a machine onto the truck comprising means for preventing the angle between the planes of the bottoms of said members becoming less than a predetermined minimum.

In testimony whereof I affix my signature.

FRANK CARTLIDGE.
